The ornamental design for an electrical stimulation device, as shown and described.

DESCRIPTION

FIG. 1 is a front view of an electrical stimulation device showing the design;

FIG. 2 is a bottom plan view thereof;

FIG. 3 is a side elevational view thereof;

FIG. 4 is a top plan view thereof;

FIG. 5 is a rear elevational view thereof;

FIG. 6 is a front perspective view thereof;

FIG. 7 is a rear perspective view thereof;

FIG. 8 is a fragmental exploded front perspective view thereof;

FIG. 9 is another fragmental exploded front perspective view thereof;

FIG. 10 is a front view of a second configuration of that shown in FIG. 1;

FIG. 11 is a bottom plan view thereof;

FIG. 12 is a side elevational view thereof;

FIG. 13 is a top plan view thereof;

FIG. 14 is a rear elevational view thereof;

FIG. 15 is a front perspective view thereof;

FIG. 16 is a rear perspective view thereof;

FIG. 17 is a fragmental exploded front perspective view thereof; and,

FIG. 18 is another fragmental exploded front perspective view thereof.

The broken lines shown represent the portions of the electrical stimulation device that form no part of the claimed design.
